[57] CLAIM

The ornamental design for a pair of reversed contracts shoes, as shown.

DESCRIPTION

FIG. 1 is a perspective view of a pair of reversed contrast shoes, showing my new design;

FIG. 2 is a top plan view thereof;

FIG. 3 is an outside elevational view thereof; and,

FIG. 4 is an inside elevational view thereof.

The broken line showing of a shoe sole is for illustrative purposes only and forms no part of the claimed design.
